UNITED STATES PATENT OFFICE

ALEXANDER McLEAN NICOLSON, OF NEW YORK, N. Y., ASSIGNOR TO WIRED RADIO, INC., OF NEW YORK, N. Y., A CORPORATION OF DELAWARE

NONCIRCULAR CONE LOUD-SPEAKER

Application filed March 11, 1927. Serial No. 174,492.

This invention relates to sound reproducing apparatus and more particularly to such apparatus comprising a relatively large direct acting diaphragm, that is, a diaphragm exposed on at least one side to unconfined air, and of sufficient size to produce sound waves of the desired strength and quality, without the use of baffle plates and the like.

It is an object of this invention to produce a sound reproducing diaphragm having a noncircular periphery, preferably made up of a pair of elements formed as a mirror image of each other, and physically united in such manner that vibrations of the one react upon and affect the vibrations of the other, thereby providing a resultant mode of vibration different from that of either of the sections alone. Still other objects of this invention will be apparent from the specification.

The features of novelty which I believe to be characteristic of my invention are set forth with particularity in the appended claims. My invention itself, however, both as to its fundamental principles and as to its practical applications, will best be understood by reference to the specification and accompanying drawing, in which:

Figs. 1, 2 and 3 are respectively front and side elevations and top plan view of one form of apparatus according to my invention.

Figs. 4 and 5 are respectively a front elevation and top plan of a modified form of apparatus according to my invention.

Fig. 6 is a front elevation of a still further modified form of my invention.

In accordance with my invention, I provide a plurality of sound radiating diaphragm sections. In accordance with one aspect of this invention, the sections are incomplete; that is, mutilated circular cones, each having a similar section cut away or omitted, parallel to the vertical axis of the cone and spaced therefrom. The diaphragm sections are secured together along this intersection and means are provided for supporting and driving these sections, preferably from the apexes of the individual sections.

In its preferred form, this driving means

comprises one or more piezo-electric crystals, but it will be understood that other driving means may be substituted therefor, such for example as an electro-magnetic unit, or the like.

In accordance with another aspect of my invention, instead of utilizing sections of circular conical diaphragms, I may use a pair of sections of elliptical conical diaphragms which may be secured together as above described, forming a sound radiating member of substantially elliptical periphery. In this instance, the diaphragm may be formed with what I term a ridge pole apex, in which the apex of the diaphragm instead of being a single point as is usually the case, is in the form of a line extending across the diaphragm, and which is secured to the supporting and driving member.

In accordance with still another aspect of my invention, the diaphragm may be provided in the form of an elliptical cone, but instead of applying the driving force at a plurality of points on the diaphragm including the focal points, the driving force is supplied to the apex which is in the form of a single point symmetrically disposed with reference to the entire diaphragm.

Referring now more particularly to Fig. 1, 1 designates a sound radiating diaphragm, comprising a pair of members 2 and 3, of paper, cardboard, wood, composition or metal, each in the form of a mutilated or incomplete circular cone, the cone 2 having an apex 4 and the cone 3 having an apex 5. A section is omitted or cut from each of the cones along a line determined by passing a plane of intersection through the diaphragm parallel to the vertical axis, but laterally spaced therefrom, and the two sections are secured together at this line of intersection 6. The driving means for the diaphragm is preferably in the form of a piezo-electric crystal device 8 such as a crystal of Rochelle salt exhibiting the well known "hour glass" configuration, provided with a pair of electrodes 9 and 10, of any suitable form such for example as an internal electrode or an electrode at one or both basal planes, and an equatorial belt electrode of 100

conducting material forming a loop around the crystal parallel to the basal plane.

5 A pair of stress plates 7 and 11 are also provided, suitably secured to the crystal as by bolting or cementing by the use of Rochelle salt "melt", formed by heating Rochelle salt at a temperature above its melting point to drive off the desired amount of water. The apexes 4 and 5 of the diaphragms 2 and 3 are secured to the ends of the stress plate 7 in any suitable manner as by cementing or bolting. The stress plate 11 is secured as by bolting upon a relatively massive base 12.

10 It will now be seen that if electrical oscillations corresponding to sounds desired to be reproduced are impressed upon the electrodes 9 and 10, the crystal device 8 will generate stresses or motions corresponding to the electrical oscillations and if the electrodes are in 15 the form of an internal and external equatorial electrode forming a loop around the crystal, the stress plate 7 will tend to oscillate upon the axis of the crystal, thereby impressing mechanical vibrations 180° out of 20 phase upon the apexes 4 and 5 of the diaphragm sections 2 and 3. Each of these diaphragms will be set into vibration by stress waves in the material travelling outwardly from the apexes toward the peripheries and 25 the reaction of these stress waves upon each other across the line of intersection 6 causes a modification of the mode of vibration of each of the diaphragm sections from what would normally obtain, thereby causing a 30 change in the quality of the sound.

35 Referring now more particularly to Figs. 4 and 5, in this instance, the diaphragm sections comprise elliptical sections 15 and 16 intersecting on the line of intersection 17. Instead of a single point apex, there may be provided what I term a ridge pole apex 18 of the section 16, and a similar apex 19 in the section 15, whereby the entire ridge pole apexes 18 and 19 may be secured to the stress plate 7.

40 It will be understood that if the line of intersection 17 passes through the exact center of each of the sections 15 and 16, the resultant diaphragm will be an ellipse. On the other hand, if the sectional line is displaced 45 to one side or the other of the center of each of the sectional diaphragms, the periphery will vary from an ellipse.

50 Referring now more particularly to Fig. 6, in this instance I have shown an elliptical cone diaphragm formed in a single piece, and having a single apex 21 in the center thereof by which the diaphragm is secured to a suitable stress plate 22 mounted on the crystal 8.

55 It will be noted that in the arrangement shown in Figs. 1 to 5 inclusive, the driving force is applied at a plurality of points on the diaphragm including the focal points, whereas in the arrangement shown in Fig. 6, this is not the case.

60 65 While I have shown and described certain

preferred embodiments of my invention, it will be understood that modifications and changes may be made without departing from the spirit and scope of my invention, as will be understood by those skilled in the art.

70 I claim:—

1. A sound reproducer comprising a relatively large rigid diaphragm comprising a plurality of mutilated conical shaped diaphragm sections physically united. 75

2. A sound reproducer comprising a relatively large rigid diaphragm comprising a plurality of substantially conical shaped diaphragms physically united with their center lines parallel the major peripheries of said diaphragms being substantially circular. 80

3. A sound reproducer comprising a relatively large rigid diaphragm comprising a pair of substantially conical shaped mutilated diaphragms extending in substantially the same plane physically united at adjacent edges with their center lines parallel and spaced apart. 85

4. A sound reproducer comprising a pair 90 of substantially conical diaphragms positioned adjacent each other with their bases in the same vertical plane, a driver for imparting sound vibrations to said diaphragms at the apexes thereof, said diaphragms merging one into the other at the junction thereof. 95

5. A sound reproducer comprising a pair 100 of substantially conical diaphragms positioned adjacent each other with their bases in the same vertical plane, a driver for imparting sound vibrations to said diaphragms at the apexes thereof, said diaphragms having segments cut therefrom, said diaphragms being joined one with respect to the other substantially along a chordal line through said diaphragms. 105

Signed at New York city in the county and State of New York this tenth day of March A. D. 1927.

ALEXANDER MCLEAN NICOLSON.
